CHARM CASE

Henri Elion, New Rochelle, N. Y.

Application December 3, 1952, Serial No. 22,539

Term of patent 7 years

(Cl. D45—15)

To all whom it may concern:

Be it known that I, Henri Elion, a citizen of the United States, residing at New Rochelle, county of Westchester, and State of New York, have invented a new, original, and ornamental Design for a Charm Case, of which the following is a specification, reference being had to the accompanying drawing, forming a part thereof, wherein:

Fig. 1 is a top plan view of a charm case showing my new design;

Fig. 2 is a front elevational view thereof;

Fig. 3 is a side elevational view thereof; and

Fig. 4 is a bottom plan view thereof.

The essential features of my design reside in the portion shown in full lines.

I claim:

The ornamental design for a charm case, substantially as shown and described.

HENRI ELION.
